ENVELOPE OPENING MACHINE

Edward J. Dummer and Azel Gay, Rochester,
N. Y., assignors to Multipost Company, Rochester, N. Y., a corporation of New York

Application October 7, 1937, Serial No. 167,773

4 Claims. (Cl. 164—61)

Our present invention relates to paper feeding and cutting machines and more particularly to envelope or mail opening machines of the type in which the letters either piled or singly may be run rapidly through and one of their marginal edges neatly slit to just remove the fold without injuring the contents, and it has for its object to provide a simple, efficient and improved machine of this character that may be conveniently operated at high speed and capacity and yet with surety of accurate performance. The improvements are directed more particularly in connection with cutters, an envelope edge guide in the feeding of envelopes thereto and an envelope conveyor or feeding device, to a novel form of presser foot having characteristics in the functioning of which it holds the particular envelope being operated upon and so conveyed in proper contact with the conveyor and with the guide regardless of the thickness of the envelope within certain limits and with due regard for the safety of its contents. To these and other ends, the invention resides in certain improvements and combinations of parts, all as will be hereinafter more fully described, the novel features being pointed out in the claims at the end of this specification.

In the drawings:

Fig. 1 is a front elevation of a letter opening machine constructed in accordance with and illustrating one embodiment of our invention;

Fig. 2 is a top plan view thereof;

Fig. 3 is a vertical section taken substantially on the line 3—3 of Fig. 1 and viewed in the direction of the arrows;

Fig. 4 is an enlarged detail sectional end view of the presser foot which allows the envelopes to climb the belt only one at a time;

Fig. 5 is an enlarged front view of the knives and the edge guide, the intervening parts being removed;

Fig. 6 is an enlarged fragmentary end view of the upper portion of the machine showing the presser foot of this invention;

Fig. 7 is a fragmentary front view of the upper feed portion of the machine on the scale of Fig. 6 and illustrating in side elevation the presser foot of this view;

Fig. 8 is a fragmentary sectional view taken transversely through the presser foot and an envelope held thereby substantially on the line 8—8 of Fig. 7;

Fig. 9 is an end view of a modified form of presser foot;

Fig. 10 is a detail front view of a further modi-

fied form of presser foot detached from its mounting, and

Fig. 11 is an end view thereof looking from the delivery end of the machine.

Similar reference numerals throughout the several views indicate the same parts.

This application is a continuation in part of our prior application, Ser. No. 117,486, filed Dec. 24, 1936, entitled Envelope opening machine, in which parent application several features looking to the objects herein generally expressed are embodied. A description sufficient to give a clear understanding of the present invention requires a repetition of the showing in some respects of the aforesaid parent application.

Referring more particularly to the drawings, 1 indicates a preferably cast base 1 having end walls 1^a and a partition-like central framework 2 rising therefrom. At the front is suitably secured a cover plate 3 and at the rear a cover plate 4 together constituting a casing within which the interior mechanism is housed. At the front a shelf-like plate 5 constitutes the bed along which the envelopes are fed and operated upon. Rising from the rear wall of this bed plate at the left end thereof in Fig. 1 is a flange 6 constituting a general rear guide wall. A transversely extending vertical plate 7 has a flange by which it is secured to the frame 2 at 8 and constitutes a gate beneath which the envelopes are fed. They are stacked on this left hand or feed end of the bed plate 5 in an inclined pile, the regularity of which is established by the guide wall 6 and the said gate 7. The downward inclination of the feed of the lower envelope is established by a shed 9 secured to the table by a screw 10 passing therethrough and into a lug 11 on the adjacent base end 1^a.

At the right hand end of the table, the frame 2 is provided with a bearing 12 in which turns a shaft 13 having at its rear end a driven pulley 14 and belt 15 by which it is turned from the driving pulley 16 of a motor 17 mounted on the base. The shaft 13 extends through the frame partition 2 and at its forward end is a hub 18 against the rear side of which is clamped securely by a nut 19 a slitting knife 20. Against the front side of the hub is similarly secured by a nut 21 a grooved pulley 22. Another grooved idler pulley 23 is suitably mounted on the frame partition 2 and over the two pulleys passes an endless feed belt 25. This feed belt is preferably of rubber and circular in cross section. Its upper reach 26 travels in slot 27 on the bed plate 5 and projects just partially above the same so as to take sure

frictional contact with an envelope on the bed while the latter is still maintained in a substantially flat condition.

Above the bearing 12 is a similar bearing 28 on the frame 2 containing a stud shaft 29. On the outer or forward end of this stud is a hub 30 against which there is clamped by a nut 31 an upper companion slitting knife 32 cooperating in the overlapping manner best shown in Figs. 3 and 5 with the driven knife 20. A housing 20^a open sufficiently at the bottom only to admit a guiding means and the envelopes, covers and protects this knife, the same being held to the frame wall 2 by screws 20^b. The stud 29 is hollow and contains a spring 33 that reacts against a plate 34 secured to the end of the bearing box by two screws 35. The knife 32 is thus urged forwardly continuously by the spring against the driven knife 20 to itself be frictionally driven by the latter.

As best shown in detail in Fig. 5, an extension 36 on the end of the back plate or guide 6 of the bed plate 5 projects toward the knives and has a tapered end 37 that enters between them at their intersection running as closely as possible to the bite or cutting point of the blades. This extension is V-shaped in cross section, as shown also in the other figures, but the bottom at the inside apex is definitely flat, as indicated at 38, lies in the plane of the guide wall 6 and this plane is sufficiently back of the cutting plane defined by the contacting surfaces of the knives to cut off the fold of the envelope edge back the desired distance. The lower plate 39 of the edge guide inclines downwardly outwardly to contact with the bed plate 5 while its longitudinal projection toward the feed end of the machine is given a compound curve into which the lateral inclination merges, whereby it also inclines downwardly at the receiving end to meet the surface of the bed plate and form a ramp portion 40 up which the envelopes slide to enter the edge guide against the wall 38. The upper plate of the V at the corresponding end has a share portion 41 where it joins the plate 6 for a similar purpose.

As so far described, in operation, the undermost letter of a pile squared against the back wall 6 and the gate 7 touches or is urged by the operator against the belt 25. It is carried under the gate and the frictional hold of the belt thereon causes it to overcome the retarding influence of a spring finger 42 on the far side of the gate having a notch 43 therein (Fig. 4) to accommodate the belt. The finger has a rounded lower edge which, however, arrests the envelope next above until the first one, whose frictional contact might otherwise carry it with it, has passed on. This adjacent one in turn contacts the superior friction of the feed belt and is next fed forward. The latter carries each envelope along the edge guide through the knives which slit the fold thereof and then passes out at the right end of the machine in opened condition.

The said retarding finger 42 is mounted on a shaft 44 extending between the securing flange and a front flange 45 of the gate plate 7 and is pressed downwardly by a spring 46 coiled about such shaft. A lug 47 on the finger carries a stop screw 48 that bears against a lug 49 on the gate 70 to limit the downward thrust of the finger with reference to the belt and to the nature of the mail matter that is passing through.

It is, of course, important that as the envelope enters the knives its edge should be firmly and evenly pressed against the wall 38 of the edge

guide so that the fold thereof will be uniformly and evenly sheared off to exactly the desired extent. This is insured by the following provisions: In the first place, the direction of travel of the upper reach 26 of the belt is not strictly longitudinally of the bed but converges inwardly from pulley 23 to pulley 22. In addition to this, the axis of pulley 23 is cocked in two planes intersecting the plane of the axis of pulley 22, as clearly appears, that is, the stud is tilted downwardly and also laterally bringing the pulleys out of line on two angles. The result is that the reach 26 of the belt twists or rotates on its own geometrical axis toward the knives as it passes from the one pulley to the other in the feeding direction. Its frictional effect on the envelope is, therefore, both to convey it in a straight path and to urge it laterally toward the knives and against the edge guide 36.

At the cutting point, the envelope is held to the knives, in one construction, by a presser foot that comprises an elongated foot portion 67 pivoted at 68 under the influence of a spring 69 that thrusts it yieldingly downward to a normal position limited by a screw 70 engaging lug 57. However, a rounded heel 71 at the rear starts very close to the finger 42 and the foot extends from there up to the median line of the knives with the toe preferably a little beyond that point, as indicated at 72 in Fig. 7. The smooth flat undersurface 73 is inclined transversely downwardly toward the edge guide 36 and the cutting plane. Longitudinally, this same surface is in parallel with the upper projecting reach 26 of the cylindrical feed belt 25 and normally but slightly spaced therefrom, so that even a thin envelope will be clamped lightly between the foot and the belt. In other words, in cross section, as in Fig. 8, the under engaging surface of the foot is not horizontal but is cocked tangentially of the surface of the belt beneath the envelope, which latter is indicated at E in the figure referred to. The result is to amplify the frictional grip that the rotating belt exerts against the envelope in urging it against the guide and into the cutting plane. The inner or depressed longitudinal edge dips the envelope at the point where reference letter E is attached in Fig. 8 downwardly around and beyond the belt while the lower plate 39 of the guide 36 directs it upwardly to the apex of wall 38. Thus, an enlarged frictional contact surface of the belt is brought into play and this inner edge of the presser foot so holds the envelope to the belt practically continuously along the edge guide 36, being definitely between it and the belt. Particularly with long envelopes, the tendency is for the rear end to twist or slew away from the cutting plane as it reaches the knives, as previously mentioned, but with this foot 67 such rear end is held in proper position to the very last of the cut.

In Fig. 9, a modification is shown in which a presser foot 50^a similarly mounted and similarly regulated is composed of a wide sheet metal stamping that presents a greater expanse of under inclined surface 59 above the belt and toward the edge guide and the cutting plane.

In conclusion, attention is called to the functional showing of Fig. 8 as indicative of the advantages inherent in all forms of the present invention. The transversely rotating belt 26 in addition to its inclination of feed urges the envelope E toward the guide 36. This guide is somewhat near the elevation of the carrying surface of the belt. Nevertheless, its lower portion 75

39 reaches down below the belt. The presser foot 73 has an inclination, as stated, downwardly over the belt toward this lower guide portion 39. As the envelope is urged laterally toward the guide, 5 it must take the curve shown insuring gripping contact with the belt. In addition, as such envelope is forced between the belt and the inclined presser foot 73, the latter has a tendency to urge the bulky contents of the envelope toward the 10 interior of the latter and away from the cutting plane of the knife blades. In this way, the knives operate only upon the envelope on a marginal edge free of the contents that otherwise might be crowded into the sphere of action of 15 the knives.

15 In Figs. 10 and 11, a presser foot block or shoe 75 is shown as a further modification, the underside of which is inclined at 76 in the same way with reference to the conveyor belt 26 and the 20 table 5. However, it is articulated centrally at 77 upon a presser foot arm 78 by means of a pivot bolt 79 pinned to the lugs 80 of the said arm. A central lug 81 on the foot takes the pivot while other lugs 82 constitute saddles for the contact 25 of a leaf spring 83 that passes through the pivot bolt 79 so locked against rotation. The said arm 78 has a bearing 84 for the stud 68, a lug 85 for a limiting screw and a shoulder 86 to take the pressure of a spring like spring 69, all as before.

30 The point of this construction is that, while in a foot of the character shown in Fig. 7 the raising of the heel 71 by the passage of an envelope thereunder will greatly increase the raising of the toe 72 with reference to parallelism to the conveyor belt, in this embodiment of Figs. 10 and 35 11 the shoe portion 75 of the foot will tilt from its center and tend to maintain parallelism with the belt under the influence of the leaf spring. A useful function thereof is that in case a thick 40 envelope precedes a thin one in travel over the conveyor, or a thin envelope precedes a thick one, the thick envelope will not hold the presser foot out of contact with the thin one altogether and hence leave the thin one without any pressure against the belt at all. In other words, the 45 shoe 75 of the foot will become adaptable and transmit at least part of its pressure to the thin one of said envelopes while also riding on the thick one.

50 We claim as our invention:

1. In an envelope opening machine, the combination with a bed plate, a knife arranged angularly thereto, an endless belt for feeding envelopes along the bed and an edge guide for the envelopes associated with the knife to direct the edge of an envelope in the cutting plane thereof, of a yielding rocking presser foot adapted to engage the edge portion of the envelope at the cutting point, said presser foot being arranged in opposition to the belt and having its under envelope contacting surface flat and inclined trans-

versely downwardly toward the cutting plane in such manner that it does not hug the belt but is purely tangential thereto.

2. In an envelope opening machine, the combination with a bed plate, a knife arranged angularly thereto, an endless belt for feeding envelopes along the bed and an edge guide for the envelopes associated with the knife to direct the edge of an envelope in the cutting plane thereof, of a yielding rocking presser foot adapted to engage the edge portion of the envelope at the cutting point, said presser foot being arranged in opposition to the belt and having its under envelope contacting surface flat and inclined transversely downwardly toward the cutting plane, 5 and a lower inclined plate on the edge guide 10 sloping reversely downwardly toward the belt to receive the envelope from the incline of the presser foot. 15

3. In an envelope opening machine, the combination with a bed plate, a knife arranged angularly relatively thereto, an endless belt for feeding envelopes along the bed and an edge guide for the envelopes associated with the knife to direct the edge of an envelope in the cutting plane 20 thereof, of a yielding rocking presser foot adapted to engage the edge portion of the envelope at the cutting point, said presser foot being arranged in opposition to the belt and having its under envelope contacting surface flat and inclined transversely downwardly toward the cutting plane, 25 and a pivoted supporting arm for the presser foot articulated therewith at a substantially central point so that the presser foot may equalize its pressure against the belt as between 30 intervening thick and thin envelopes riding between them. 35

4. In an envelope opening machine, the combination with a bed plate, a knife arranged angularly relatively thereto, an endless belt for feeding envelopes along the bed and an edge guide for the envelopes associated with the knife to direct the edge of an envelope in the cutting plane thereof, of a yielding rocking presser foot adapted to engage the edge portion of the envelope at the cutting point, said presser foot being arranged in opposition to the belt and having its under envelope contacting surface flat and inclined transversely downwardly toward the cutting plane, 40 a pivoted supporting arm for the presser foot articulated therewith at a substantially central point so that the presser foot may equalize its pressure against the belt as between 45 intervening thick and thin envelopes riding between them, and a spring acting between the supporting arm and presser foot to transmit a 50 balancing pressure on the two ends of the presser foot. 55
